UNITED STATES PATENT OFFICE.

PASCAL J. SHAMPAY, OF CHICAGO, ILLINOIS, ASSIGNOR TO SHAMPAY BROTHERS, OF CHICAGO, ILLINOIS, A CORPORATION OF ILLINOIS.

CLEANING MACHINE.

1,281,425.

Specification of Letters Patent. Patented Oct. 15, 1918.

Application filed June 19, 1914, Serial No. 846,062. Renewed May 30, 1918. Serial No. 235,737.

To all whom it may concern:

Be it known that I, PASCAL J. SHAMPAY, a citizen of the United States, residing at Chicago, in the county of Cook, State of Illinois, have invented certain new and useful Improvements in Cleaning - Machines, of which the following is a specification.

This invention relates to cleaning machines, more particularly described as a carpet cleaning machine for dusting, scrubbing and rinsing rugs, carpets and the like. This invention relates to an improved machine of this kind, and among the objects of the invention are,—to provide means, in carpet cleaning, for dusting without scrubbing; scrubbing without dusting; to employ a single drum for drawing the article to be cleaned through the dusting, scrubbing, scraping and rinsing apparatus; to provide 10 an automatic water feed, which is operated when the machine is started; to drown and carry off the dust with the rinse water; to exhaust the dust from both sides of the article to be cleaned; to provide a beating apparatus which incloses all of the article to be cleaned in a closed chamber; to provide a counterbalanced hood for the beating device, which is pivotally mounted and adjustable on the same axis as the drum; to make the 15 drum adjustable toward and from the scrubbing brushes for taking up the wear of said brushes; to provide in the dusting chamber a yielding support for the article cleaned, whereby the beaters will act upon the article as it lies upon the yielding support, and to provide means for discharging the dust from the dusting chamber and the waste cleansing fluid from the cleansing apparatus.

For the attainment of these ends, and the 20 accomplishment of other new and useful objects, as will appear, the invention consists in the features of novelty in the construction, combination and arrangement of the several parts generally shown in the accompanying drawings and described in the specification, and more particularly pointed out in the appended claims.

In the drawings,—

Figure 1 is an end elevation with parts 25 shown in section of a machine constructed in accordance with the principles of my invention;

Fig. 2 is an end elevation of the machine at the other end thereof, some of the parts being broken away for clearness;

55

Fig. 3 is a sectional view taken on the line 3—3 of Fig. 1, and

Fig. 4 is a sectional view of the machine transversely of the drum.

This invention relates to a machine for 60 completely cleaning rugs, carpets and the like, and comprises apparatus for beating the carpet, for brushing the dust and dirt loosened by the beating operation, and continuously drawing the carpet through the 65 beating apparatus and from the dusting brush through a scrubbing apparatus, comprising brushes which throw a cleaning fluid into the nap of the carpet, and then in 70 scraping, rinsing and brushing the carpet to cause the nap to lie in a single direction and at the same time removing any of the cleansing fluid from the nap of the carpet.

To carry out this operation, a rotatable drum 6 is mounted in standards 7 at the ends 75 thereof, in which are adjustable bearing supports 8, each comprising a shaft 9 movable up and down by means of a worm 10 and gear 10* (see Fig. 4). At one end, the drum is provided with a gear 11, engaged by 80 a driving worm 12 mounted on a shaft 13, which in turn receives its power from a gear 14 mounted on the drive shaft 15.

Supported by the standards 7 is a sectional 85 housing, comprising a lower portion 16 and a separable upper portion 17, the latter of which rests upon the former and is connected at its ends to beams 18 having counterweights 19 and pivoted on the shaft of the drum 6, so that the upper portion of the 90 housing 17 may be rotated about the shaft of the drum toward and from the lower portion 16 of the housing. In the upper portion of the housing is a rotatable beater 20, comprising a plurality of slappers 21, the beater 95 comprising a shaft 22 which extends through the housing at one end and is provided with a gear 23, rotated by means of a chain 24. At this end of the drum (see Fig. 1), the standard 7 is provided with a support 25 in 100 which is mounted a sprocket 26 about which the chain 24 passes, the sprocket 26 being substantially co-axial with the drum 6, so that when the upper portion 17 of the housing

ing is raised by rotating the beams 18 about the shaft of the drum the chain 24 will still be in engagement with its sprocket 26. Secured to or formed integral with the sprocket 26 is a driving gear 27, which meshes with a gear 28 also mounted in the support 25, which carries a sprocket 29. Mounted on the shaft 15 is a driving sleeve 30, to which is secured a driving sprocket 31, about which 10 passes a driving chain 32 connected with the sprocket 29. Also mounted in the dusting device housing is a dusting brush 33, driven by means of a sprocket 34, a chain 35 and a sprocket (not shown) on the driving sleeve 30. An adjustable spring-opposed bearing, 15 comprising a hand tightener 34', is provided at each end for moving this brush toward and from the drum 6 to take up wear of the brush or for tightening the chain 35. A clutch 36 connects the driving sleeve with the shaft 15, and the clutch is operated by means of a lever 36' near the clutch, a connecting link 37 extending under the machine, and a lever 38 at the other end of the 20 machine. It will be observed that the beating device and the dusting brush are rotated in opposite directions, the dusting brush being rotated in the direction of rotation of the drum 6, so that the article to be cleaned 25 is brushed against its direction of movement as it comes from the dusting machine.

In the lower portion 16 of the housing is a reticulated support 39, in which the article to be cleaned is disposed. Extending 30 upwardly from near the reticulated support 39 is a plate 40, under which the dusting brush 33 is disposed. The upper edge of the plate is disposed adjacent the drum 6, and secured to the upper edge of the plate 40 are a plurality of flexible members 41, preferably formed of canvas, leather, or some other flexible material, spaced apart and the lower ends extending around a rod 42 above the reticulated support 39. Connected to 45 the ends of these flexible members 41 and to the plate 40 are springs 43, which permit the members 41 to give longitudinally. The beating device is disposed so that the slappers 21 engage a piece of material to be cleaned as it lies upon these flexible members 41 and is moved over them. The resiliency of the members 41 permits a yielding impact of the slappers 21 and allows the carpet cleaned to vibrate with the members, 50 which prevents injury to the carpet. The members 41 are spaced from the plate 40 and permit the dust and dirt to fall freely from the lower side of the article cleaned.

In the bottom of the housing 16 is a discharge fan 44, and along the edge of the upper portion 17 of the housing is an air suction chamber 45, provided at the bottom with yielding flaps 46 disposed adjacent the surface of the article to be cleaned. This

suction chamber 45 communicates at one end 65 with a passage 47, which is formed at the bottom with an opening 48 registering with a passage 49 in communication with the bottom of the lower housing portion 16. When the upper housing portion is closed upon the lower portion, the passages 47 and 49 register, so that air and dust will be drawn from the chamber 45 by means of the fan 44, and of course the air and dust will be drawn from the bottom portion 16 of the chamber 75 by the same fan, so that the dust will be sucked from both sides of the article to be cleaned.

In order to draw the article to be cleaned from the dusting device and over the flexible members 41, a clamping device 50 is provided in connection with the drum, and comprises a slot 51 in the drum, into which the end of the member to be cleaned is placed, and a yielding rod 52, which is pressed against the end of the member to be cleaned already inserted in the slot, holding it firmly in place and of sufficient yielding qualities to fill the slot 51 beyond the sides of the article to be cleaned when the article to be cleaned 80 is narrower than the full width of the drum, so that the cleansing fluid will not be thrown into the open slot as it passes the cleansing brushes.

Arranged next in order below the drum 85 are cleansing brushes 53 and 54, rotatable in opposite directions and arranged in a chamber 55 formed by the plate 56. These brushes are provided on the outside of the chamber with meshing gears 57 and 58 at one end, and one of them is provided at the other end with a sprocket 59, driven by means of a chain 60 and a sprocket 61 freely mounted on the shaft 15 and connected thereto by a releasable clutch connection 62. It will thus be seen that these cleaning or 90 scrubbing brushes can be controlled independently.

Disposed within the chamber 55 is a spring-pressed cradle 63, which carries a soap tube 64 having a plurality of apertures 65, each controlled by a separate valve 66. Connected at one end to each valve is a holder 67, the other end of which is connected to a cross piece 68 mounted in the cradle. These holders 67 are disposed above one of the scouring brushes 53 and are adapted to be engaged by the article to be cleaned on the drum as it is drawn past the cleaning brushes. These holders 67 are also 110 for the purpose of preventing the brush 53 from disengaging the rear end of the article to be cleaned from the drum as the said article is drawn by the drum past this brush. It will be apparent that the article 115 to be cleaned will open valves 66 only the width of the article itself, so that no more of the cleansing fluid than is needed will be 120 125

discharged from the tube 64. The cleansing fluid is discharged into the chamber 55, and is thrown by the brushes 53 and 54 into the nap of the carpet or rug, the warp thereof being disposed against the surface of the drum. Extending upwardly in this chamber 55, at the end thereof, almost to the axis of the uppermost brush, is a drain 55', which extends from the chamber 55 to the dust chamber 10 in the housing 16. This discharge permits the passage of the foam and used fluid from the cleaning chamber 55, and is very effective in carrying off the dust and dirt which is drawn from the article cleaned in the dust-removing housing, the dust and particles of dirt being carried off by the foam and fluid and discharged by means of the discharge fan 44. This discharge 55' does not prevent the cleaning 15 brushes from dipping into the cleaning fluid at the bottom of the chamber 55.

Next in order is the rinsing operation, which is effected in a chamber 69 disposed below the chamber 55. In this chamber on 20 the shaft 15, rotating in the direction opposite to the rotation of the drum, is a rinsing brush 70, and disposed in advance of the brush is a spray pipe 71 with apertures 72 disposed to direct the rinsing fluid into the nap 25 of the carpet as it passes, whereupon the brush 70 will act upon the carpet both to remove the cleaning and rinsing fluid from the carpet and to lay the nap thereof all in the same direction. Attached to the plate 56 is 30 a wiper 74, preferably formed of rubber or the like, to remove dirt and the surplus cleaning liquid from the surface of the article to retain it in the chamber 55, and to prevent the liquid from being thrown from 35 the chamber 55. A spring-pressed cradle 73 is also mounted in this chamber 69 and carries a flexible scraper or wiper 74^a similar to the one mounted on the plate 56. Intermediate the two wipers 74 and 74^a are scrapers 40 74^b, also mounted on the cradle 73 and movable with it toward and from the drum. The cradles 73 consist of connected end pieces having rollers bearing on the drum adjacent the ends and springs tending to 45 press each cradle against the drum. These scrapers are preferably constructed of spring metal and operate to clean and remove any dirt or foreign material left in the article cleaned after it passes the cleaning 50 chamber.

Connecting the bottom of the chamber 69 with the bottom of the chamber in the lower housing portion 16 is a pipe connection 75, by means of which the cleansing fluid is discharged in with the dust and dirt from the dusting device. The used cleansing fluid, soapy discharge from the cleansing brushes, and the dust and dirt from the dusting device being all discharged into this compartment

at the bottom of the housing member 16, causes the dust, foam and fluid all to be thrown together, so that when removed by means of the discharge fan 44 there is no flying dust or dirt.

Connected with the rinsing pipe 71 is a pipe 76, in which is a valve 77 controlled by means of a rod 78. The rinsing fluid is supplied through a pipe 79, in which is a three-way valve 80. Connected to the three-way valve 80 is a by-pass pipe 81, which leads to the bottom of the chamber 69, so that the rinsing water may be discharged directly from the source of supply through the chamber 69 and through the pipe 75 to the dust chamber, and through the exhaust fan 44 when only the dusting operation is being performed. At this time the clutch 62 would, of course, be thrown out, preventing the scouring brushes from operating. The valve 77 may be automatically controlled by means of the rod 78 and by means of a ridge 82 in connection with the drum, and a lever 83 contacting therewith, to one end of which the rod 78 is connected. This ridge is so arranged that the valve 77 is open when the machine is started, or when the edge of the article to be cleaned reaches the rinsing pipe. In cleaning a carpet or rug, it may be drawn entirely through the dusting, cleaning, scraping and rinsing devices by the drum itself. This is the normal operation, and is ordinarily employed for articles less in length than the circumference of the drum. If it is desired to clean a piece of a length greater than the circumference of the drum, it is obvious that some other means must be employed for drawing the article to be cleaned through the different cleaning devices, and at the same time maintaining the article to be cleaned in contact with the drum during its passage through the cleaning devices. For this purpose, an auxiliary feed comprising gripping rolls 84, 85, is provided, one of which rolls is preferably provided with teeth 86 and is movable up and down, by means of a rack 87 and pinion 88 at each end connected to a hand wheel 89, in order to pass the end of the article to be cleaned between the rolls. Adjacent the periphery of the drum 6 and supported by the standards 7 is a roller 90, over which the article to be cleaned must be passed before it is drawn between the rolls 84 and 85. In this operation, the article to be cleaned is first attached to the drum by the gripping device, as before, and the drum is rotated until the gripped end is drawn beyond the roller 90 in the proper direction, after which the drum is stopped, the gripping device is released and the gripped end of the article to be cleaned is passed between the rolls 84 and 85. A driving connection from the shaft 15 to a shaft 91 of one of the

gripping rolls 84 comprises a shaft 92 and worm gears 93 and a clutch 94.

From this description, the operation of the machine will be readily understood.

5 The shaft 15 is the driving shaft and is ordinarily provided with a drive pulley 95, about which a belt 96 passes for transmitting power from any suitable source of supply. The fan 44 may be run by a separate 10 driving connection 97 from the same or a different source of power. As previously explained, the beater and the dusting brush may be left idle while the cleaning brushes are continued in operation, or the cleaning 15 brushes may be left idle while the beater and dusting brush are operated. In either case, however, the brush 70, which is directly mounted on the shaft 15, is operated, for the function of this brush is to remove any 20 pernicious dirt from the nap of the rug and at the same time to comb the nap so that it will all lie in the same direction.

I claim:

1. In a carpet cleaning machine, a rotatable drum, a carpet beating device adjacent the drum, and a fluid scrubber below the drum, the drum drawing a carpet loosely through the beating device and forming a solid backing for the carpet as it is drawn 30 through the scrubber.

2. In a carpet cleaning machine, a rotatable drum, a carpet beating device adjacent the drum, a support for loosely holding a carpet, a fluid scrubber below the drum, 35 means for attaching the edge of a carpet to the drum for drawing it loosely through the beating device, and a dusting roll for pressing a carpet against the drum as a backing while the carpet is drawn through the 40 scrubber.

3. In a carpet cleaning machine, a beater, a fluid scrubber comprising brushes, means on the drum to engage the edge of a carpet to draw the carpet through the beater and to 45 form a backing for the carpet as it is drawn through the scrubber, means for operating the beater and simultaneously and independently, and means for raising the drum to clear said brushes when the beater is independently operated.

4. In a carpet cleaning machine, a beater and a dusting brush with a common enclosure into which dirt falls, a fluid scrubber with a receptacle which receives the used 55 fluid, and connections for discharging the said fluid through the said dirt enclosure to carry off the dirt in said fluid.

5. In a carpet cleaning machine, a beating device which operates on one side of a carpet, a suction exhausting means having passages with openings adjacent a carpet on the same side as the beating device, means for drawing a carpet through the beating device, the beaten side of the carpet resting

against said means, and fluid scrubbing 65 mechanism which operates on the outer side of the carpet and against said means.

6. In a carpet cleaning machine, a rotatable drum for the carpet to be cleaned, and a beating device having a rotatable member 70 and means for mounting the member for bodily movement coaxially with the drum.

7. In a carpet cleaning machine, a rotatable drum for the carpet to be cleaned, and a beating device having a rotary beating 75 member, and a counterbalanced pivotal mounting to raise the member clear of the side of the drum.

8. In a carpet cleaning machine, a beating device comprising a separable housing, the 80 upper portion of which is pivotally mounted, and a rotary beating member mounted in the pivoted portion of the housing; and means to draw the carpet loosely through the beating device.

9. A cleaning machine of the class described, comprising a rotatable drum, a separable housing, the upper portion of which is co-axially mounted with respect to the drum, a beater rotatable in the upper portion of the housing, and driving means for said beater, comprising a driving sprocket co-axial with the drum.

10. In a cleaning machine of the class described, a separable housing the upper part 95 of which is movable with respect to the lower, a support in the lower portion of said housing for the article to be cleaned, a beater in the upper portion of said housing, flexible members secured in the lower portion of said housing against which the article to be cleaned bears when the beater operates upon it, and means for drawing the article to be cleaned over the said flexible members.

11. In a carpet cleaning machine, a beating device in which the carpet is loosely supported, a rotatable drum for carrying the carpet and drawing it from the beating device, a dusting brush adjacent the beating device rotatable in a direction to hold the 110 carpet against the drum and to allow the carpet in the beating device to be loosely supported, and fluid cleansing brushes operable upon the carpet backed by the drum after the carpet passes the dusting brush.

12. In a carpet cleaning machine, the combination with carpet dusting means, of scrubbing means, fluid rinsing means, and a single rotary drum provided with means attachable to one edge of a carpet for drawing 120 a carpet through the said cleaning means in the order named.

13. In a combined dusting, scrubbing and rinsing machine, the combination of dusting mechanism embodying a dust receptacle, 125 scrubbing mechanism, comprising a fluid chamber, rinsing mechanism, embodying a cleaning fluid chamber, a single means for

drawing an article to be cleaned through all of said mechanisms, pipe connections from the said fluid chambers to the dust receptacle, and discharging means in connection with the dust receptacle whereby the fluid from the other receptacles and the dust are carried away.

14. In a carpet cleaning machine for dusting, scrubbing and rinsing, the combination with a water feed for rinsing, of a drum to draw the article to be cleaned through the rinsing mechanism, and drum operated means for controlling the water feed.

15. In a combined carpet dusting, scrubbing and rinsing machine, the combination with a dust chamber, of a receptacle for containing waste rinsing fluid, a water-feed mechanism for rinsing, means for controlling the water for rinsing, a by-pass for the water to the rinsing receptacle, and a connection from the rinsing water receptacle to the dust chamber whereby water may be discharged to the dust chamber from the waste rinsing water receptacle through said by-pass without operating the rinser.

16. In a combined carpet dusting, scrubbing and rinsing machine, the combination with a rotary drum for carrying the article to be cleaned during the several operations, of a dusting device, means to connect the device with the drum for operation when the drum is rotated, scrubbing mechanism, comprising rotary brushes, rinsing mechanism, comprising a rotary brush, means connecting the scrubbing and rinsing brushes for simultaneous operation, a separable connection for operating all of said brushes simultaneously with the drum, and means to raise or lower the drum whereby the machine can dust without scrubbing and scrub without dusting.

17. In a carpet cleaning machine, a rotatable drum for carrying the article to be cleaned, a soap discharge pipe, and a spring-pressed support for the soap pipe tending to press it toward the drum.

18. A carpet cleaning machine, comprising a rotatable drum to carry the article to be cleaned, and a supplementary feeder comprising a gripper adapted to be driven continuously with the drum for discharging a continuous strip of cleaned material from the drum after it has been drawn partially through by the drum.

19. In a cleaning machine of the class described, the combination with a rotatable drum, of cleaning mechanism, comprising rotatable brushes, a spring-pressed cradle adjacent said brushes, a soap discharge pipe, valves therefor, and wire holders secured to the cradle and to said valves adapted to be engaged by the article to be cleaned as the drum rotates, whereby the valves will be opened only for the width of the article

to be cleaned and the end of the article to be cleaned will be held against the drum and prevented from disengagement therefrom by the contact of either of the said brushes with it.

20. In a carpet cleaning machine, a rotatable drum to support and move the article to be cleaned, a spring-pressed cradle, and scrapers mounted upon the cradle adapted to be pressed thereby in the direction of the said drum to assist in removing dirt from the article to be cleaned as it is drawn past the scrapers by said means.

21. In a cleaning machine of the class described, the combination with a continuously rotatable drum for drawing the articles to be cleaned through the cleaning operations, and an auxiliary feeding device comprising a roller disposed adjacent the outside of the drum, gripping rolls one of which is adjustable to engage the end of the article to be cleaned after it has been drawn through the cleaning operation by the said drum, and means to operate the said gripping device continuously with the drum whereby a continuous length of material can be cleaned, the drum and the auxiliary gripping means acting in conjunction to draw the article cleaned through the several cleaning operations.

22. In a cleaning machine of the class described, a rotatable drum for carrying the article to be cleaned, and a pivotally mounted and rotatable beating device bodily movable with respect to the drum about its pivot.

23. In a carpet cleaning machine, a rotatable drum provided with means for engaging one edge of the carpet for carrying the carpet and drawing it through the cleaning operations, and a beating device at the side of the drum comprising a beater movable out of beating position to provide space at the side of the drum for attaching a carpet to said engaging means of the drum.

24. In a carpet cleaning machine, the combination with a rotary drum for supporting the carpet, of a cradle spring pressed toward the drum, a cleaning fluid discharge pipe with valves therefor to engage a carpet on the drum, and wire holders connected to the cradle and said valves to insure that the valves will be opened only for the width of the carpet on the drum.

25. In a carpet cleaning machine, the combination with a rotary drum for supporting the carpet, of a spring pressed cradle, and wires carried thereby, and a cleaning brush which tends to ruffle and disengage the carpet, but is prevented by the wires which hold the carpet against the drum.

26. In a carpet cleaning machine, a supporting casing, an endless conveyer, means thereon for connecting the end of a carpet thereto, pneumatic dust removing means ad-

jacent said conveyer at one side of the carpet, means including a brush, for directing a washing fluid against the opposite side of the carpet, and another brush mounted to act against the said opposite side of the carpet in cleaning it.

27. In a carpet cleaning machine, a supporting casing, an endless conveyer, means thereon for connecting the end of a carpet thereto, pneumatic dust removing means adjacent said conveyer with a part thereof against the carpet, means including a brush, for directing a washing fluid against one side of the carpet, another brush for cleaning mounted to act against this side of the carpet, and a squeezing device arranged to act against the carpet after it has been acted upon by said brushes.

28. In a carpet cleaning machine, an endless conveyer, means thereon for connecting the end of a carpet thereto, pneumatic dust collecting means adjacent said conveyer with a part thereof near the carpet, means for directing a washing fluid against one side 25 of the carpet, brushes mounted to act against this side of the carpet, means for directing a rinsing fluid against the carpet between said brushes, and a squeezing device arranged to act against the carpet after it has been acted upon by said means and brushes.

29. In a carpet cleaning machine, an endless conveyer, impact means arranged adjacent said conveyer to act upon the carpet while it is traveling, pneumatic dust removing means having a part thereof adjacent

the carpet, means including a brush for conducting a cleaning fluid against one side of the carpet, a dusting brush arranged adjacent said conveyer to act upon the carpet in advance of the cleaning fluid, and a receptacle beneath said dusting brush.

30. In a carpet cleaning machine, an endless conveyer, impact means arranged adjacent said conveyer to act upon the carpet while it is traveling, a dust collector adjacent said means, a brush arranged adjacent said conveyer to act upon the carpet, means including other brushes for directing a cleaning fluid against one side of the carpet, a dirt receptacle beneath said first brush, and means for conducting a rinsing fluid against the cleaned side of the carpet after it passes the fluid cleaning means.

31. In a carpet cleaning machine, an endless conveyer, means for connecting the end of a carpet thereto, means including a rotatable brush for scrubbing one side of the carpet with cleansing fluid as the carpet is drawn past by the carrier, means for then applying rinsing fluid to the carpet, and another rotary brush to act upon the carpet after the application of rinsing fluid.

In testimony whereof I have signed my name to this specification, in the presence of two subscribing witnesses, on this 15th day of June, A. D. 1914.

PASCAL J. SHAMPAY.
